COMBINATION SPECTACLE AND COIN CASE

Loretta B. White, Evanston, Ill.

Application November 8, 1949, Serial No. 5,933

Term of patent 14 years

(Cl. D57—1)

To all whom it may concern:

Be it known that I, Loretta B. White, a citizen of the United States, residing at Evanston, in the county of Cook and State of Illinois, have invented a new, original, and ornamental Design for Combination Spectacle and Coin Case, of which the following is a specification, reference being had to the accompanying drawing, forming part thereof.

Fig. 1 is a front elevational view of a combination spectacle and coin case, showing my new design.

Fig. 2 is a perspective view looking at an angle toward the front and downwardly.

Fig. 3 is a side elevational view.

I claim:

The ornamental design for a combination spectacle and coin case, as shown and described.

LORETTA B. WHITE.
